UNITED STATES PATENT OFFICE

2,390,820

SPARK PLUG UNIT BUSHING

Thomas N. Willcox, Pittsfield, Mass., and Hubert H. Race, Schenectady, N. Y., assignors to General Electric Company, a corporation of New York

Application October 11, 1943, Serial No. 505,730

12 Claims. (Cl. 174—167)

Our invention relates to bushings particularly adapted to provide a fluid seal about the connection of a spark plug unit to an ignition lead. Such a seal is very necessary to prevent sparkover of a spark plug terminal at high altitudes.

An object of our invention is to provide an improved bushing for a spark plug unit.

Another object of our invention is to provide an improved sealing bushing for a radio shielded ignition spark plug unit adapted to provide a good electrical contact between different elements of the radio shielding system.

Further objects and advantages of our invention will become apparent and our invention will be better understood from the following description referring to the accompanying drawing, and the features of novelty which characterize our invention will be pointed out with particularity in the claims annexed to and forming part of this specification.

The drawing illustrates a bushing partly in section embodying our invention.

Referring to the drawing, we have shown an embodiment of our improved bushing for a radio shielded ignition spark plug unit which includes a relatively rigid tubular insulating terminal boot 10 formed of a suitable insulating material, such as a ceramic or boro-silicate mica and having an inwardly extending flange 11 adjacent the lower end thereof. In order to provide a fluid seal about a conductor adapted to be arranged in the bushing, a relatively resilient and yieldable insulating sleeve made of any suitable material, such as a heat and corona resistant synthetic rubber, is formed with a portion 12 which extends into the boot 10 from the upper end thereof to the flange 11 and is intimately bonded to the inner surface of the boot in any suitable manner, as by molding it onto a roughened, cemented, or otherwise appropriately prepared surface, to provide a lining through substantially the full length of the boot. A collar 13 is formed on the resilient sleeve and extends over the upper edge of the boot 10 to provide a resilient cushion over the upper surface of the boot, and an upper tubular section 14 extends from the collar away from the boot and is formed of a thicker section than the portion of the sleeve 12 which extends into the boot to provide a substantially gas-tight seal of a spark plug well and thereby to improve high altitude operation. An electrically conductive metallic washer 15 having a central opening therethrough which is larger than the passageway through the resilient sleeve is secured by bonding in the collar 13 and extends outwardly therefrom to provide

an electrical connection between cooperating engaging surfaces of adjacent radio shielding elements for the ignition system. This bushing provides the desired rigid terminal boot together with a resilient and yieldable insulating sleeve bonded to the boot to insure against electrical discharges between the surfaces of the boot and the sleeve from the terminal of an ignition conductor to ground and also provides for the desired good electrical contact between the cooperating radio shielding elements of an ignition system.

While we have illustrated and described particular embodiments of our invention, modifications thereof will occur to those skilled in the art. We desire it to be understood, therefore, that our invention is not to be limited to the particular arrangement disclosed, and we intend in the appended claims to cover all modifications which do not depart from the spirit and scope of our invention.

What we claim as new and desire to secure by Letters Patent of the United States is:

1. A bushing for a spark plug unit including a rigid tubular insulating terminal boot, and a resilient insulating sleeve extending into said boot and intimately bonded to the inner surface thereof and having a collar extending over the upper end of said boot.
2. A bushing for a spark plug unit including a relatively rigid tubular insulating terminal boot, and a relatively resilient insulating sleeve extending into said boot and bonded to the inner surface thereof having a collar extending over the upper end of said boot and an upper tubular section extending from said collar away from said boot.
3. A bushing for a spark plug unit including a rigid tubular insulating ceramic terminal boot, and a resilient insulating sleeve extending into said boot and intimately bonded to the inner surface thereof having a collar and an upper tubular section extending from said collar away from said boot.
4. A bushing for a spark plug unit including a rigid tubular insulating boro-silicate-mica terminal boot, and a resilient insulating sleeve extending into said boot and intimately bonded to the inner surface thereof having a collar and an upper tubular section extending from said collar away from said boot.
5. A bushing for a spark plug unit including a relatively rigid tubular insulating terminal boot, and a relatively resilient insulating sleeve extending into said boot and bonded to the inner surface thereof for providing a lining through

substantially the full length of said boot, said resilient sleeve having a collar and an upper tubular section extending from said collar away from said boot.

6. A bushing for a spark plug unit including a relatively rigid tubular insulating terminal boot having a roughened inner surface, and a relatively resilient insulating sleeve extending into said boot and bonded to said inner surface thereof of having a collar extending over the upper end of said boot and an upper tubular section extending from said collar away from said boot.

7. A bushing for a radio shielded spark plug including a rigid tubular insulating terminal boot, a resilient insulating sleeve extending into said boot and bonded to the inner surface thereof having a collar and an upper tubular section extending from said collar away from said boot, and an electrically conductive washer element bonded in said collar and extending outwardly therefrom.

8. A bushing for a spark plug unit including a relatively rigid tubular insulating terminal boot, a relatively resilient insulating sleeve extending into said boot and bonded to the inner surface thereof having a collar extending over the upper end of said boot and an upper tubular section extending from said collar away from said boot, and an electrically conductive washer element bonded in said collar and extending outwardly therefrom.

9. A bushing for a spark plug unit including a relatively rigid tubular insulating terminal boot, a relatively resilient insulating sleeve extending into said boot and bonded to the inner surface thereof having a collar and an upper tubular section extending from said collar away from said boot, and an electrically conductive element having a central opening therethrough larger than the passageway through said resilient sleeve bonded in said collar and extending outwardly therefrom.

10. A bushing for a spark plug unit including a relatively rigid tubular insulating terminal boot, a relatively resilient insulating sleeve extending into said boot and bonded to the inner surface thereof for providing a lining through substantially the full length of said boot, said resilient sleeve having a collar and an upper tubular section extending from said collar away from said boot, and an electrical conductive washer element bonded in said collar and extending outwardly therefrom.

11. A bushing for a radio shielded ignition spark plug unit including a relatively rigid tubular insulating terminal boot, a relatively resilient insulating sleeve extending into said boot and bonded to the inner surface thereof having a collar extending over the upper end of said boot and an upper tubular section extending from said collar away from said boot, and an electrically conductive element having a central opening therethrough larger than the passageway through said resilient sleeve bonded in said collar and extending outwardly therefrom.

12. A bushing for a radio shielded ignition spark plug unit including a relatively rigid tubular insulating terminal boot, a relatively resilient and yieldable insulating sleeve extending into said boot and bonded to the inner surface thereof for providing a lining through substantially the full length of said boot, said resilient sleeve having a collar extending over the upper end of said boot and outwardly therefrom and an upper tubular section extending from said collar away from said boot, and an electrically conductive washer element having a central opening therethrough larger than the passageway through said resilient sleeve bonded in said collar and extending outwardly therefrom.
